UNITED STATES PATENT OFFICE

1,979,549

PORTABLE REFRESHMENT STAND

John F. Huckel, Kansas City, Mo.

Application November 10, 1932, Serial No. 642,003

4 Claims. (Cl. 62—13)

My invention relates to a portable refreshment stand and more particularly to one of wagon type which may be propelled over the floor or platform of a railway station for service of cool drinks, ice cream cones, and the like, to passengers in waiting rooms, or in railway coaches, or over the floor of an auditorium or the like for service to spectators or participants of a large gathering of people.

10 As the invention is particularly directed to an apparatus for dispensing cool liquid or solid refreshments, it is an object of the invention to provide apparatus in which the refreshments may be maintained at desirably low temperatures, and as the apparatus is particularly intended for use in floored enclosures, it is a further object of the invention to avoid soiling of the floors over which the device is propelled by dripping of the refrigerant employed for cooling.

20 It is a further object of the invention to provide a sanitary device of the character stated of attractive appearance and arrangement, and convenient for customers and attendants.

25 In accomplishing these and other objects of the invention, I have provided improved details of structure, the preferred form of which is illustrated in the accompanying drawing, wherein:

Fig. 1 is a perspective view of a refreshment 30 wagon embodying my invention.

Fig. 2 is a longitudinal vertical section on an irregular line extending centrally through the refreshment compartment and through an adjacent utility section.

35 Fig. 3 is a transverse vertical section through a part of the frame particularly illustrating the supporting wheel mounting.

Fig. 4 is an enlarged section through a corner of the wagon body, particularly illustrating the 40 drainage control.

Referring more in detail to the drawing:

1 designates end sills and 2 a center sill extending transversely of the wagon and supporting the floor 3 of a body portion thereof, the 45 floor preferably consisting of boards 4 and 5 and an intervening body 6 of heat insulating material.

Enclosing the sills and floor and rising thereabove, are side and end walls 7, preferably of 50 sheet metal, reinforced by edge, corner and intermediate strips 8, 9 and 10 and seated on the floor between the side and end walls are tanks 11, preferably of metal and square in cross section to conform to the contour of the wagon body; the walls 55 of the tanks being spaced from the side and end

walls of the wagon body and from each other to provide spaces for non-heat-conductive material 12, the ends of the tanks being preferably provided with reinforcing metal sheets 13.

Seated on the floor within one of the compartments is a tank 14 adapted for containing liquid refreshment, such as orange juice, or the like, and of a diameter to provide a space thereabout for suitable refrigerant 15, such as cracked ice which may be salted to provide a cooling brine.

60 Seated on the floor within the other compartment is a perforated cylinder 16 adapted for containing an ice cream can 18 of ordinary construction, including a cover 19. One end of the body portion just described is extended by prolongations of its side walls to provide storage space for utilities or the like, and preferably equipped with drawers 20 movable laterally into and from spaces within the extension on suitable supports such as rails 21. The drawers are preferably of a length 65 to provide space adjacent one side of the wagon to accommodate a suspended receptacle 22 for an ice cream dipper 23, or other utility.

70 The entire top of the wagon, including the body part and end extension is covered by a main 75 top 24 and the separate tanks provided with individual cover portions 25 and 26, one provided with a door 27 for providing access to the ice cream can and the other adapted for carrying pump equipment of ordinary construction, preferably including a main pump 29 extended to the bottom of the tank 14 and having an operating lever 30 and nozzle 31 exposed above the lid.

75 I also prefer to provide an auxiliary vessel 32 for storage of flavors and to suspend the auxiliary 80 vessel from a sub-lid 33 on the main lid 28 and provide for service of the liquid flavoring with a pump 34 in accordance with common practice.

85 The utility receptacle in the other end of the body may be suspended from the main top of the 90 top member and made accessible through a door 95 35.

The wagon body is supported on a pair of main 100 wheels 36 journaled on suitable axles 37 mounted on the ends 38 of a bar 39 attached to the under side of the central sill 2 and upturned at the sides of the body, as by this form of mounting the wagon body may be carried closer to the ground and thereby provide for a maximum capacity for a minimum elevation of the top of the wagon.

105 To stabilize the wagon, I mount a third caster wheel 40 in a yoke 41 attached to a bar 42 extending rearwardly from one end of the wagon body within the extended portion, the bar 42 being 110 preferably spaced from the bottom plane of

the body to conform to the low mounting arrangement of the body on the ground wheels.

A hand bar 43 is provided at the rear end of the wagon body for assistance of the attendant for propelling and guiding the wagon.

In one corner of each of the refreshment storage tanks is a partition 44 (Fig. 4) slightly raised from the bottom of the tank to provide a port 45 and mounted on the floor of the tank within the

10 compartment formed by said partition is a plate 46 having an outlet port 47 leading to a drain conduit 48. Mounted on the plate 46 is a guide yoke 49 and extending through the guide yoke near the top of the tank is a rod 50 having a valve 15 51 at its lower end yieldingly urged to seat in the port 47 by spring 52 surrounding the rod and bearing at its respective ends against the end of the guide yoke and the top of the valve. The rod 50 is provided with a handle 53 at its upper end.

20 A wagon constructed and assembled as described, with its tanks supplied with ice cream and with liquid drink refreshments, may be propelled over a floor or platform so that prospective customers may be served according to their 25 wishes in the same manner as the same service would be given from a permanent refreshment stand or fountain, the refreshments being kept at proper temperatures by the refrigerant with which the containing tanks are surrounded.

30 Ice melting in the tanks is first converted to cooling brine but retained in the tanks by the drain valves to prevent dripping onto the floor or platform. The melted ice or brine may, when desired, be removed from the tanks by lifting of the drain control valves.

35 It is apparent that I have provided a refreshment wagon which not only provides for convenient accommodation of the public, but for convenient operation by an attendant and that the device is not only attractive in appearance but sanitary and cleanly both as to the wagon proper and the flooring over which it is conveyed.

40 What I claim and desire to secure by Letters Patent is:

45 1. In apparatus of the character described, a water tight compartment having a vertical partition spaced from the bottom of the compartment to provide a primary chamber for retaining a refrigerant and a secondary chamber having

50

connection at the bottom of the partition with the primary chamber for flow of liquid from the primary to the secondary chamber, the secondary chamber having a drain outlet in its bottom for the liquid, a valve for said outlet, and valve operating means extending upwardly in the secondary chamber for access at the top of the compartment.

2. In apparatus of the character described, a compartment, having a top opening providing access to a container in the compartment and adapted for supplying refrigerant to the compartment about the container, and having a bottom drain outlet, a valve for said outlet, valve operating means accessible through said top opening, and a partition for retaining refrigerant in said compartment from contact with the valve operating means, the partition being spaced from the bottom of the compartment to permit discharge of liquid from the refrigerant zone to said outlet.

3. In apparatus of the character described, a water tight compartment having a vertical partition spaced from the bottom of the compartment to provide a primary chamber for retaining a refrigerant and a secondary chamber having connection at the bottom of the partition with the primary chamber for flow of liquid from the primary to the secondary chamber, the secondary chamber having a drain outlet in its bottom for the liquid, a valve for said outlet, and an operating rod connected with said valve and extending upwardly in the secondary chamber for access at the top of the compartment.

4. In an apparatus of the character described, a rectangular shaped compartment having a top opening providing access to a container in the compartment and adapted to supply refrigerant to the compartment about the container and having a bottom drain outlet in a corner thereof, a valve for said outlet, valve operating means accessible through said top opening, and a partition extending across said corner for retaining refrigerant in said compartment from contact with the valve operating means, the partition being spaced from the bottom of the compartment to permit discharge of liquid from the refrigerant zone to said outlet.
